H. MUEHLE

FASTENING DEVICE

Filed Sept. 11, 1922

INVENTOR:

Norman Muehle
By his attorney

Lawrence B. Muller.

UNITED STATES PATENT OFFICE.

HERMAN MUEHLE, OF CLEVELAND, OHIO.

FASTENING DEVICE.

Application filed September 11, 1922. Serial No. 587,547.

To all whom it may concern:

Be it known that I, HERMAN MUEHLE, a citizen of the German Republic, residing at 10,009 Kennedy Ave., Cleveland, in the State 5 of Ohio and Cuyahoga County, have invented a new and useful Improvement in Fastening Devices, of which the following is a specification, the principle of the invention being herein explained and the best 10 mode in which I have contemplated applying that principle so as to distinguish it from other inventions.

My invention relates to a fastening device and more particularly to a strong, simple, 15 durable structure, and sufficiently economical of manufacture to commend itself commercially as a quickly operable clamp for miscellaneous uses. The drawings exemplify its use as a clothes line clamp.

20 Adverting to the drawing:

Figure I is a front elevation showing a device embodying my invention carried by a fixture such as a clothes pole and showing it in its clamped position to hold the clothes 25 line taut.

Figure II is a side elevation viewed on line II—II of Figure I.

Figure III is a view corresponding to Figure II showing the position assumed by 30 the parts of my device when in its unclamping position with its jaw open.

Figure IV is a horizontal section on line IV—IV of Figure I looking downwardly.

A back or supporting member 1 is firmly 35 secured to a fixture 2 by means of a plurality of screws 3. Projecting forwardly and then upwardly from the member 1 are a pair of spaced hooks 4 across which is mounted a pin 5 acting as a pivot for a clamping member including a depending counter weight 6 40 and an upstanding clamp 7 which is movable toward and away from the support 1 between the hooks 4 and which has its side which is opposed to the support serrated at 45 8 after the manner of clamping jaws. The depending weighted end 6 acts normally to tilt the jaw 7 by gravitational action to the open position shown in Figure III.

Pivotedly connected with a rivet 9 which 50 is secured to the support 1 at a point below the end of the weight 6 is an operating lever 10 provided with a handle 11 and fashioned with a cam surface 12 located behind the weighted end 6 and adapted when turned to shove and hold it outwardly as illustrated in Figure II thereby simultaneously moving

the jaw 7 toward the support 1 so that a rope 13 may be clamped therebetween.

In operation, when the lever 11 is in its depending position as shown in dotted lines of Figure I the depression in the cam surface 12 will be uppermost, thus allowing the weighted end 6 to assume the position shown in Figure III and thereby carry the jaw 7 to its open position. A clothes line may then be looped around the hooks 4 and when drawn taut may be readily so held by simply throwing the lever 11 upwardly to the position shown in full line in Figure I. The operation is easy and quickly effected.

70 I claim:

1. A device of the character described comprising the combination of a support, a clamping member pivotally mounted on said support and adapted gravitationally to assume an inutile position, and an actuating lever connected with said support for moving said member to its clamping position.

2. A device of the character described comprising the combination of an upright support, a clamping member pivotally mounted on said support and adapted to swing in a substantially vertical plane, and an actuating lever fashioned with a cam surface for moving said member toward said support whereby to clamp an object therebetween.

3. A device of the character described comprising the combination of a support carrying an upstanding hook, a contrivance 90 including a double armed lever adapted to move in a substantially vertical plane and one arm thereof across the bight of said hook to press against said support and a clamp actuating member pivotally carried 95 by said support and fashioned with a circular cam adapted to move between said support and the other arm of said lever.

4. A device of the character described comprising the combination of a support 100 fashioned with a hook, a counterweighted clamping member movably mounted on said hook and adapted to move toward and away from said support and means for actuating said member toward said support whereby 105 to clamp an object therebetween.

5. A device of the character described comprising the combination of a support, a lever having an intermediate portion pivotally mounted thereon, one part of said lever 110 being adapted to act as a clamp in conjunction with said support, and wedging means

for engaging the other part of said lever to shift it to its clamping position.

6. A device of the character described comprising the combination of a support, a double armed lever pivotally mounted upon a substantially horizontal axis on said support, the upper part of said lever being adapted to act as a clamp in conjunction with said support, wedging means adapted 5 for interpositioning between said support and the lower part of said lever to rock the upper to its clamping position.
- 10 7. A device of the character described

comprising the combination of a support, a structure movably mounted on said support 15 and including a clamp adapted to co-act therewith and also including a counterweight normally tending to move said clamp to its inutile position, and an actuating device connected with said support for engaging said counterweight to move said clamp to its clamping position.

Signed by me, this 29th day of August, 1922.

HERMAN MUEHLE.
